UNITED STATES PATENT OFFICE

170,251

HAT

Samuel Weinstein, New York, N. Y.

Application July 17, 1952, Serial No. 20,652

Term of patent 3½ years

(Cl. D3—13)

To all whom it may concern:

Be it known that I, Samuel Weinstein, a citizen of the United States, residing in New York city, county of New York, State of New York, have invented a new, original, and ornamental Design for a Hat, of which the following is a specification, reference being had to the accompanying drawings, forming a part hereof.

Figure 1 is a perspective view of a hat, showing my new design.

Figure 2 is another perspective view thereof, showing the side opposite to that disclosed in Figure 1.

The essential features of my design reside in the row of perforations through the body of the hat which are bordered by two applied felt strips that are brought together and superimposed at one side of the hat, as shown in solid lines.

I claim:

The ornamental design for a hat, substantially as shown and described.

SAMUEL WEINSTEIN.
